UNITED STATES PATENT OFFICE.

CLARK C. NELSON, OF ROCKY FORD, COLORADO.

TOBACCO MIXTURE.

1,338,089.

No Drawing.

Specification of Letters Patent. Patented Apr. 27, 1920.

Application filed February 3, 1919. Serial No. 274,712.

To all whom it may concern:

Be it known that I, CLARK C. NELSON, a citizen of the United States of America, and a resident of Rocky Ford, Otero county, and 5 State of Colorado, have invented certain new and useful Improvements in Tobacco Mixtures, of which the following is a specification.

My invention relates to tobacco and has 10 special reference to tobacco mixtures which are adapted for smoking.

One object of my invention is to provide a smoking mixture that will make a clear smoke and leave a clean taste in the mouth 15 after smoking, which will minimize the detrimental effect on the nerves of the user.

Another object is to provide a clean, wholesome substitute for clear tobacco which shall be mild and satisfactory, and harmless 20 to the user and inexpensive to manufacture.

More specifically, it has been my aim to make a tobacco blend composed of from one-half to two-thirds tobacco and from one-third to one-half of a sugar producing 25 vegetable. I prefer to utilize sugar beet pulp from which the sugar has been removed by the usual commercial processes which leave a certain sweetness in the pulp.

The beet pulp is thoroughly dried and

broken up so that it has the size and appearance of smoking tobacco. It is then mixed with a desired grade of smoking tobacco by any suitable stirring or mixing apparatus, and then the mixture is ready to be put up 30 in packages or cartons, ready for use.

I believe I am the first to suggest a mixture of this character and the mixture which I prefer has been satisfactorily used by smokers who are accustomed to the use of tobacco and it has been found a perfectly satisfactory substitute for clear tobacco. It is particularly adapted for use by 40 young men and others who desire a mild smoke and the low cost at which it can be produced and sold is a decided advantage in 45 favor of the man whose means are limited.

What I claim is:

1. A smoking tobacco blend composed of a mixture of smoking tobacco and dried sugar beet pulp.

2. A smoking tobacco blend composed of from one-half to two-thirds smoking tobacco, and from one-third to one-half of sugar beet pulp.

In witness whereof I have hereunto set 55 my hand this 28th day of January, 1919.

CLARK C. NELSON.
